MEANS FOR OPENING CONTAINERS

Charles Richard Logic, South Milwaukee, Wis.

Application June 8, 1949, Serial No. 79,736

2 Claims. (Cl. 222—86)

1

This invention relates to means for opening sealed containers in combination with means for the removal of the contents of the container.

Containers of the type for the storage of liquids and particularly, containers for the storage of condensed milk may be opened in a number of ways. A particularly simple and often used method is by the use of piercing prongs whereby the upper portion of the container is pierced with one or more openings through which the contents may be removed. Punch type can openers are well known. However, when cans are so pierced and the contents, as for example, condensed milk is removed at intervals, there is a tendency for a residue of condensed milk to collect about the opening and present an untidy appearance as well as cause a disagreeable odor.

It now has been discovered that a container may be provided with a pair of openings by means of a hand press punch type can opener which functions, in addition to piercing the can, as a means for providing a facile, efficient and sanitary method for removing the contents of the can.

The invention is now more fully disclosed by referring to the drawing in which:

Fig. 1 is a plan view partly in section and with parts removed showing the device of this invention in operative position.

Fig. 2 is a top view of Fig. 1.

Fig. 3 is an enlarged view taken on the line 3—3 of Fig. 2.

Fig. 4 is a modified form of the piercing prong of the device of this invention.

Fig. 5 is a view taken on the line 5—5 of Fig. 4.

Referring to the drawing in detail, the combination can-opener and pouring spout is clearly shown in Fig. 1 indicated generally at 1 in which the device comprises a circular housing 2 having a base portion 3 from which extends downwardly a skirt or lip portion 4. The base portion 3 is provided with a threaded insert 5 adapted to receive the piercing prong 6.

The piercing prong 6 is provided with a centrally located opening 7 which terminates near the point end 8 of the prong 6 in a pair of openings 9. These openings 9 interconnect with each other and the central opening 7 to provide a passage through the piercing prong 6 for the removal of the liquid contents of the container 10. The base portion 3 is provided with an opening 11 in axial alignment with the threaded aperture 5 and with the opening 7 of the piercing prong 6 after the prong is moved into threaded engagement with the threaded aperture 5.

2

The piercing prong is further provided with a resilient sleeve 12 which is positioned on the shank of the prong 6 and rests on the shoulders 13 formed by the piercing point 8 of the prong 6 and the shank portion. The upper end of the shank portion of the prong 6 is threaded to be received in locking engagement with the threads of the recess 5.

A pouring spout 14 is formed on the housing 2 and is provided with an opening 15 which extends in axial alignment with the opening 11 and horizontally outwardly to the edge of the housing 2.

When it is desired to remove the contents of the container 10, the can opener 1 is placed onto the upper end of the can 10 so that the can is received within the skirt 4 and is contacted with the points 8 of the piercing prongs 6. Pressure is then applied to the base 3 of the device 1 until the prongs 6 are forced through the upper portion of the container to provide an opening 16 therein. A liquid tight seal is produced between the edges 17 of the opening 16 and the resilient sleeve 12. The device is thereby held firmly in position with the can and provides an opening from the interior of the can to its exterior through the openings 9, 7, 11 and 15. The contents of the can is removed by rotating the can in the direction of either one of the two piercing prongs causing the liquid to enter the openings 9 passing now downwardly through the openings 7 and 11 and then into the passage 15 and outwardly toward a receptacle in a controlled manner of flow by opening or closing the other passage 15 by placing a finger of the operator over the opening 15. When a sufficient quantity of material has been removed from the container, the container is placed in its normal upright position and the contents that filled the passages 9, 7, 11 and 15 is caused to reverse its direction of flow and return to the interior of the container. In the process of returning, the force at which the contents flows causes a self-cleansing action of these passages, thereby leaving them free to permit further removal of the contents of the container in a free and unhampered manner.

If it is desired to entirely remove the top of the can 10, a modified type of prong 17 shown in Figs. 4 and 5 may be used in place of the prongs 6. The prong 17 is provided with cutting edges 18. The prong 17 is also provided with a passage way 19 which communicates with the passage way 15 in the housing 2. The prong 17 is also provided with a resilient sleeve 20 which

functions in the same manner as does the resilient sleeve 12 on the prong 6. The prong 17 may also be provided at its upper end with a threaded portion for engagement with the threaded recess 5 in the housing 2. The prong 17 is positioned in such a manner that one of the leading edges 18 will cut the top from the container 10 when the housing 2 is rotated in either a clockwise or counterclockwise direction.

In using prongs of the type shown in Figs. 4 and 5 to remove the top of the container 10, it is necessary to back off the device 1 to a sufficient distance to disengage the sleeves 20 from contact with the metal portion of the can and engage the cutting edge 18 with the metal can cover.

The housing 2 may be made of any suitable material and it is preferred to use a thermoplastic moldable composition but metal or wood may be used. The resilient sleeves 12 and 20 may be made of rubber or any of the rubber substitutes. The piercing prongs are to be made of a metal, and particularly, a non-rusting type of metal, particularly an alloy of steel and chromium.

Although the invention is described with respect to specific embodiments shown in the accompanying drawing, it is not intended that the details thereof shall be construed as limitations upon the scope of the invention except to the extent incorporated in the following claims.

I claim:

1. A container puncturing device comprising a body having a passage-way extending from one side to another side of said body, a two sided spade-shaped piercing prong carried by said body and adapted for movement into piercing engagement with a container, said prong having a passage-way in interconnecting relationship with the passage-way of said body whereby the contents of said container may pass to the ex-

terior through said passage-ways, said piercing prong having a leading and trailing cutting edge formed at the juncture of said two sides and adapted to cut said container upon rotation of said device, and means carried by said prong for holding said device in operating position with said container.

2. A container puncturing device comprising a body having a depending skirt for centering said body on a container and a passage-way extending from one side to another side of said body, a two sided spade-shaped piercing prong carried by said body to one side thereof and adapted for movement into piercing engagement with a container, said prong having a passage-way in interconnecting relationship with the passage-way of said body whereby the contents of said container may pass to the exterior through said passage-ways, said piercing prong having a pair of cutting edges formed at the juncture of said two sides, one edge cutting said container upon rotation of said device in one direction and the other of said edges cutting said container upon rotation of said device in the opposite direction, and means carried by said prong for holding said device in operating position with said container.

CHARLES RICHARD LOGIC.
